Attorney

UNITED STATES PATENT OFFICE.

TROY ALMOND LEONARD BOWEN, OF TULSA, OKLAHOMA.

STEEL-DERRICK REINFORCEMENT.

Application filed November 6, 1924. Serial No. 748,185.

To all whom it may concern:

Be it known that I, TROY A. L. BOWEN, a citizen of the United States, residing at Tulsa, in the county of Tulsa, State of Oklahoma, have invented a new and useful Steel-Derrick Reinforcement; and I do hereby declare the following to be a full, clear, and exact description of the invention, such as will enable others skilled in the art to which

10 it appertains to make and use the same.

The invention relates to reinforcing means for the corner uprights of steel derricks of the type used for drilling oil and gas wells, and wherein said uprights are formed from angle iron, and has for its object to provide means whereby elongated bars rectangularly shaped in transverse cross section may be easily and quickly attached to the uprights for bracing the same, and materially increasing

20 the strength of the derrick as a whole.

A further object is to provide right angularly shaped plates adapted to receive the inner corner of the reinforcing wooden bar and the angle iron upright, and bolts right angularly disposed in relation to each other and connecting the flanges of the right angularly shaped plates.

A further object is to provide the flanges of one of said right angularly shaped plates 30 with apertures for the reception of the bolts, and the apertures with enlarged portions through which the bolt heads or nuts may be easily passed, thereby allowing the device to be easily and quickly applied or removed.

35 With the above and other objects in view the invention resides in the combination and arrangement of parts as hereinafter set forth, shown in the drawing, described and claimed, it being understood that changes in 40 the precise embodiment of the invention may be made within the scope of what is claimed without departing from the spirit of the invention.

In the drawing:—

45 Figure 1 is a side elevation of a portion of a conventional form of oil derrick, showing the braces applied thereto,

Figure 2 is a horizontal sectional view taken on line 2—2 of Figure 1.

50 Figure 3 is a perspective view of one of the angular plates.

Figure 4 is a perspective view of the other angular plate.

55 Referring to the drawing, the numeral 1 designates a conventional form of oil derrick, which derrick comprises the corner

uprights 2, which are formed from angle iron, and brace members 3, which are of the usual construction. It has been found that the corner uprights 2 bend and break under excessive loads, and to obviate this difficulty the brace is primarily designed. The corner uprights 2 are braced by means of rectangularly shaped wooden bars 4. Each bar 4 has its corner 5 disposed between the flanges 6 of the upright 2 and is held in close and binding engagement with the upright by means of oppositely disposed angular plates 7 and 8. Angular plate 7 engages the outer side of the upright 2 and is provided with angularly disposed outwardly extending flanges 8^b through the apertures 9 of which the clamping bolts 10 extend. It will be noted that the bolts 10 are in parallel relation to the adjacent outer sides of the bar 4, and are at a right angle to each other. The angularly shaped plate 8 is secured to the inner side of the brace bar 4 by means of a screw 11, and has its flanges provided with extensions 8^a extending beyond the corners 12 of the bar and through its portions 8^a the bolts 10 extend. The portions 8^a of the angularly shaped plate 8 are provided with right angularly shaped apertures 13, and when in position extend through the restricted portion 13^a, and are provided with nuts 14, whereby the angularly shaped plates 7 and 8 may be securely drawn towards each other for forcing the wooden bar 4 into close binding engagement with the upright 2. However to facilitate the attaching of the bolts 10 to the angular plate 8, the apertures 13 are provided with enlarged portions 13^b through which the nuts 14 will easily pass, thereby allowing the plates to be easily attached or detached from each other without removing the nuts 14 entirely from the bolts, consequently the brace members may be easily and quickly attached to the derrick upright, for thoroughly bracing the same.

100 From the above it will be seen that a derrick bracing means is provided, which is simple in construction, the parts reduced to a minimum, and one wherein the device may be easily and quickly applied to a derrick.

The invention having been set forth what is claimed as new and useful is:—

1. The combination with a corner upright of a derrick formed from angle iron, of reinforcing means therefor, said means comprising a rectangular shaped bar, said bar

having one of its corners disposed within the angle iron, right angularly shaped plates carried by the angle iron and the bar and oppositely disposed, and right angularly disposed bolts connecting the plates together.

2. The combination with a corner upright of a derrick formed from angle iron, of reinforcing means for said angle iron, said means comprising a rectangularly shaped bar, one corner of said bar being disposed within the angle iron, right angularly shaped plates carried by the outer sides of the angle iron and bar, right angularly disposed outwardly extending flanges carried by the plate engaging the angle iron, means for se-

curing the bar plate to the bar, apertures carried by the outer ends of the bar carried plate and having enlargements, bolts extending through the outwardly extending flanges of the outer plate and disposed at a right ²⁰ angle to each other and extending through the reduced portions of the apertures in the inner plate.

In testimony whereof I have signed my name to this specification in the presence of ²⁵ two subscribing witnesses.

TROY ALMOND LEONARD BOWEN.
